UNITED STATES PATENT OFFICE

DAVID FORBES KEITH, OF TORONTO, ONTARIO, CANADA

REFRIGERATING DEVICE

Application filed July 26, 1928. Serial No. 295,548.

My invention relates to refrigerating devices, particularly of the type in which a structure is provided which operates on the absorption principle, and which requires removal from the refrigerator cabinet for the purpose of generation.

Such devices include a receptacle serving as a generator-absorber, and a receptacle serving as a condenser-evaporator, with connecting conduits so arranged as to provide two passages for the gases, one from the surface of the liquid absorbent, and one from below the surface thereof, with some suitable type of seal or valve which prevents any flow 10 from the condenser-evaporator to the generator-absorber except to a point below the level of the absorbent, and any flow from the generator-absorber to the condenser-evaporator except from above the surface of the 15 absorbent.

In my pending application Serial No. 201,904, filed June 27, 1927, I have described an apparatus whereby I provide for an efficient absorption unit, designed to be lifted 20 out of the refrigerator cabinet, in order to apply heat to the generator-absorber, and cold to the condenser-evaporator during the generation and condensation of refrigerant.

It is the object of my present invention to 25 improve in some respects upon the structure of my said application. One of the improvements lies in the provision of means whereby I increase the condensation of absorbent during the step of generation (known as dehydration), by means of supplying water directly to the top of the generator-absorber shell, and preferably by forcing the gases evolved during generation to pass around the water-cooled portion of the generator-absorber shell.

Incidental to this I also provide means whereby the sounder or whistle which gives warning upon completion of the process of generation, is made more efficient and brought under better control.

Another object is to provide for a more efficient and more readily manufacturable safety valve device, and to increase dehydration in the tubular passage between the generator-absorber and the condenser-evapora-

tor by a simple structure, setting up a spiral path for the generated gases.

In the drawings:

The figure is a section taken through the device centrally and longitudinally.

55

As in my pending application, there are two spherical containers, the container or ball 1 being the generator-absorber, and the container or ball 2 being the condenser-evaporator. A tubular shell 3 is connected to the top of the ball 1, as by soldering or welding, and terminates at its other end in a sump 4, closed at the bottom as at 5. A tube 6 extends from the interior of the ball 2, into the top of the sump portion of the tubular shell 3, and has an orifice 7 on its under side.

Upon the top of the tubular portion 3 is a handle 8 for manipulating the device, which handle has a shoe 9 thereon, upon which the structure can be rested upon a table or floor, and which defines a draining position for the device, prior to the generating step of its operation.

This draining position is so defined that a vessel 10, located within the tubular shell just 75 above the tube 6, will receive, when the device is righted from said draining position, a sufficient supply of liquid to permit it to act as a dehydrator during the generation step.

In my present device this vessel 10, open at 80 the top and closed at the bottom, is surrounded by a spirally arranged wire 11 which forces the generated gases to pass in a spiral path around the outside of the vessel, thus exposing them fully to the dehydrating action. Whatever 85 of the absorbent liquid is caused to precipitate out of the refrigerant gas by this dehydration falls into the sump.

A pipe 12 extends through the top of the ball 1 into the interior of the main tubular shell, and terminates at a point just below the upper level of the spent absorbent. During the evaporation portion of the cycle of operations the refrigerant from the ball 2 passes through the tubular shell 3 and then through 95 the pipe 12 and into the absorbent.

Around the pipe 12, shortly beneath the top of the ball 1, is placed an umbrella shaped plate 13, which serves as a baffle for a purpose to be described.

100

The generated gases formed largely of the refrigerant pass out of the ball 1 into the tubular shell 3 through a pipe 14, and into the closed vessel or trap 15, from which a tube 16 extends down to a point below the upper level of the pipe 12.

The space in the tubular shell 3 below the top of the pipe 12, is used as a liquid seal, and the presence of the trap acts to assist in preventing a sudden surge of pressure from driving the sealing liquid into the ball 1, thus destroying the operation of the device.

Around the top of the ball 1 is formed a chamber 17 by means of an annular channel-shaped piece of sheet metal solder to the tubular shell 3 and to the ball 1. Instead of having a separated chamber around the top of the ball, as in my first case, I provide for direct contact of water with the top of the ball 1.

This chamber is kept full of water by means of a bleed fitting 18, which has a set screw 19 therein, for regulating the size of the outlet passage.

25 Into the chamber wall is also set a whistle 20 which communicates with the interior of the chamber.

In the operation of the device the ball 1 is submerged in water after the gases have been generated for a short interval to effect an initial reduction in pressure of the air and gases within the ball, thus starting the absorption-evaporation cycle. This operation will permit water to flow in through the bleed fitting.

30 During the generation cycle when the ball 1 is subjected to heat, the water held in the chamber 17 will turn into steam which will escape from the chamber through the bleed hole. By the time the water falls below the level of the whistle tube, and the heat has progressed sufficiently to start considerable of a boil, the bleed fitting will not carry off the steam which will pass through the whistle giving warning that the generation is complete.

35 During generation of the gases from the absorbent, i. e., while the ball 1 is being heated, the gases rise through the ball and encounter the umbrella-like baffles which causes them to traverse the top wall of the ball. This wall is directly cooled by the water held therein, thus effecting an initial dehydration of the gases, so that the absorbent collects and drips back into the supply within the ball. 40 The liquid seal also imparts dehydration to some extent, and the dehydrating chamber located above the sump completes the dehydration.

In a small portable and inexpensive apparatus, it is quite essential that dehydration of the gases be made very completely or else the efficiency of operation is not at all satisfactory.

45 My improvements in directly cooling the top of the generation ball, together with the

preferable use of the baffle within the ball, impart considerable improvement over my former device, and the spiral path enforced in the other end of the main conduit gives a further effectiveness to dehydration at that point over my former structure.

Having thus described my invention, what I claim as new and desire to secure by Letters Patent, is:—

1. In a refrigerating device of absorption type, a generator-absorber casing, a condenser-evaporator casing, passageways between them including a seal, and means for retaining a cooling liquid in direct contact with the generator-absorber casing about that portion thereof through which the generated gas passageway extends, and an alarm for indicating the completion of a generation cycle associated with said means.

2. In a refrigeration device of absorption type, a generator-absorber casing, a condenser-evaporator casing, passageways between them, said generator-absorber casing having a spherical shape, a hollow shell secured about the top of said casing to form a water receptacle located about the generated gas outlet passageway from the casing, with the water resting directly on the casing, and an alarm for indicating the completion of a generation cycle associated with said shell.

3. In a refrigeration device of absorption type, a generator-absorber casing, a condenser-evaporator casing, passageways between them, said generator-absorber casing having a spherical shape, a hollow shell secured about the top of said casing to form a water receptacle located about the generated gas outlet passageway from the casing, with the water resting directly on the casing, and a baffle within the casing causing generated gases to traverse the water engaging portion of the casing in order to reach the said passageway, and an alarm for indicating the completion of a generation cycle associated with said shell.

4. In a refrigerating device of absorption type, a generator-absorber casing, a condenser-evaporator casing, passageways between them including a seal, and means for retaining a cooling liquid in direct contact with the generator-absorber casing about that portion thereof through which the generated gas passageway extends, and baffling means within the casing causing generated gases to traverse that portion, and an alarm for indicating the completion of a generation cycle associated with said means.

5. In a refrigerating device of the character described, the combination with the casing of a generator-absorber chamber, of a warning to give audible signal of the completion of generation, comprising a receptacle for cooling water mounted on the generator-absorber casing, a whistle therein terminating within the casing toward the high water mark therein, a bleed fitting from said casing for

escape of steam and vapor and influx of water.

6. In a refrigerating device of the character described, the combination with the casing of a generator-absorber chamber, of a warning to give audible signal of the completion of generation, comprising a receptacle for cooling water mounted on the generator-absorber casing, a whistle therein terminating within 10 the casing toward the high water mark therein, and a bleed fitting from said casing for escape of steam and vapor and influx of water.

7. In a refrigerating device of the character described, the combination of a generator-absorber casing, a condenser-evaporator casing, and a tubular casing between them, of liquid retaining chambers in direct contact with generated gases as they leave the generator-absorber and just prior to their entrance into the condenser-evaporator, and an alarm for indicating the completion of a generation cycle associated with said chambers.
